PUMP WITH CONTROLLABLE DELIVERY.

1,321,278.

Specification of Letters Patent. Patented Nov. 11, 1919.

Application filed January 19, 1918. Serial No. 212,738.

To all whom it may concern:

Be it known that I, LOUIS HENRI LIBERT BELLEM, citizen of the Republic of France, and resident of Paris, France (post-office address 6 Rue St. Philippe du Roule,) have invented a new and useful Pump with Controllable Delivery, which improvements are fully set forth in the following specification.

The object of the present invention is a pump with a controllable delivery particularly intended for use in supplying combustible fuel to internal combustion engines.

The accompanying drawings show by way of example the pump of the present invention.

Figure 1 is a vertical section of the improved pump.

Fig. 2 is a similar view showing a different working stage of the pump.

Figs. 3 and 4 show the pump adjusted for a different delivery.

Fig. 5 is a modification on a larger scale.

a is a plunger of quenched and annealed steel having an extension *b* of larger diameter and sliding in a guide *c*, the latter being screwed concentrically into the cylinder *d* in which a constant level *x*, *y*, is maintained by any known means. The tight bottom of the cylinder *d* is formed by a member *e* of quenched and annealed steel carrying a conical seat *f*. On said member is mounted the discharge valve *g* consisting for example of a leather cup arranged as shown in the drawings. *h* is the pump body proper, which carries at its lower end a conical seat *i* fitting on the cone *f*.

The packing *j* consists of cork washers disposed within a cylindrical member *l* and tightly compressed between that member and the member *h*. The cork is elastic and stands wear and tear in a remarkable manner. The quenching of the plunger *a* is necessary in order to prevent it from being worn down by the cork.

The length of the complete body of the pump consisting of the cylindrical members *h* and *l* is such that there is a play of about 1 mm. at *m* when the cones *f* and *i* are in contact.

The pump works in the following manner:

Assuming that the two seats *f* and *i* are in contact, when the plunger *a* is raised the friction of the packing *j* causes said plun-

ger *a* to lift the cylindrical member *l*, until the latter strikes against the shoulder of the guide *c*. While the plunger continues its up stroke, the cylinder fills freely and without fear of any air being drawn in, the whole being immersed in the liquid. The first effect of the downstroke is to bring the two seats into contact, whereupon the discharge of the liquid is effected through pipe *o*. It should be remarked that there is no vertical force sufficient to cause separation of the two seats, the vertical force being counteracted by the plunger *a*.

By acting on the handle *p* the guide *c* is unscrewed for a short distance as shown in Figs. 3 and 4. The plunger *a* carrying the cylindrical member *l* only commencing its actual suction stroke when said member *l* comes in contact with the guide *c*; the amount of liquid drawn up is thus reduced by an extent which is proportional to the increase of the play *m*.

Thus by merely adjusting the position of the shoulder of the guide *c* the delivery of the pump can be controlled at will.

The plunger is operated by any of the usual means for instance an eccentric or cam movement.

In the modification shown in Fig. 5 the plunger 1 terminates in a guide member 2 of larger diameter and provided with a slot 3 in which engages the nose of a skeleton cam 4, the latter being mounted on a pivot 4' and actuated by an interior cam 5 secured to a spindle 5.

The drawings show the plunger at the top of its stroke. The plunger 1 slides in a body consisting of a cylindrical member 6 and a plug 7. A number of cork washers forming a stuffing gland are superimposed and compressed in the cylindrical member 6; cork having as aforesaid the remarkable property of being almost indestructible and exerting a practically constant friction on the plunger 1. The guide 2 of the plunger 1 slides in a sleeve 8 in one side of which is cut a rack engaging with a pinion 9 operated from the outside; this arrangement allows the position of the sleeve 8 to be varied in the vertical direction. The chamber 10 is always full of petrol which enters through the opening 11. A vent 10' provided in the upper portion of said chamber 10 enables all the air to be exhausted from

said chamber. The chamber 19 housing the cam 4 is filled with a highly viscous oil or thick fat.

Contrary to the arrangement of the previously described modification the valves situated in the upper part of the apparatus are arranged in such manner that they may act at any speed.

14 is a thin metal washer disposed with-
10 in a box 16; this washer bears on an elastic washer 15 preferably of fiber or ebonite, one face of which is flat while the other is hemispherical as shown in the drawings. The two washers are shut up in the box 16 by
15 means of a plug 17 provided at its lower part with a hemispherical recess the curvature of which corresponds to that of the elastic washer 15, the other face of the plug being flat.

20 The metal washer 14 and the fiber washer 15 lie free in their box so that they can adjust themselves exactly according to the plane of the end of the cylindrical member 6. When the latter rises the above described
25 valve adjusts itself and the parts 14, 15 and 17 come into firm contact under the force of the plunger 1 transmitted by the cork to the cylinder 6. The delivery is effected through a flat valve 13 arranged above the
30 aforesaid valve 14, 15, said valve 13 being controlled by a weak spring 18 which acts on the spherical outer surface thereof in order to press the valve uniformly against its seat.

35 To avoid the inconvenience which would result if the valve 13 could be too easily lifted after the delivery stroke, a spring 12 arranged in the lower part below the guide 2 maintains always good contact between the upper end of the cylinder 6 and the
40 washer 14.

The drawings show a spiral spring 12 housed in the lower part of the sleeve 8, but it will be evident that any other form of spring could be employed below the sleeve 8.

The apparatus works in the following manner:-

45 The plunger 1 being at the top of its stroke and the cam shaft 5 continuing its movements, the cam 4 remains at first in a stationary position and the cylindrical member 6 is pushed against the washer 14 by the spring 12 arranged below the guide 2. The cam 5' comes then into contact with the lower interior part of the cam 4 and the plunger 1 descends and carries with it the movable member 6, in consequence of the friction of the cork contained in said member. This member 6 consequently moves away from the flat seat 14 and its lower end makes contact with the flanged sleeve 8 the position of which has been arranged and adjusted for the desired delivery, by
60 means of the piston 9. At this moment the

down stroke of the member 6 is stopped while that of the plunger 1 continues. The liquid thereupon enters at the top of the member 6 under the influence of the suction produced by the plunger 1. As the movement of the cam 5' continues, the plunger rises and carries with it the member 6 until said member comes into contact with the flat washer 14 which arrests its stroke. The plunger 1 thereupon discharges the liquid, which it has sucked in, through the automatic non-return valve 13, arranged above the passage provided in the valve device (14, 15, 16, 17) controlling the intake into the interior of the cylindrical member 6.

In order to lessen the delivery it is sufficient to act upon the pinion 9 and thus lower the stop 8. The relative displacement of the plunger 1 and the cylindrical member 6 is thus diminished and consequently the delivery is reduced. The delivery can be reduced to any desired extent, delivery becoming zero when the space between the base of the cylindrical member 6 and the top of the stop sleeve 8 is equal to the constant stroke of the plunger 1.

In the case of a multi-cylinder engine there will be as many plungers as there are cylinders, the whole being inclosed in the same casing, the necessary precautions being taken to avoid the leakage of the oil or fat from said casing.

I claim:-

1. In a pump of the character described, the combination of a plunger; means for reciprocating the plunger; a cylindrical pump body immersed in the liquid to be pumped and through which the plunger extends, said pump body adapted to move with said plunger; a centrally-perforated washer against which the upper end of the pump body is adapted to contact during the discharge stroke of the plunger; and an elastic member disposed upon the upper face of said washer and having a central perforation in register with the perforation in the washer.

2. In a pump of the character described, the combination of a plunger having an extension which forms a guide therefor; means for reciprocating the plunger; a cylindrical pump guide immersed in the liquid to be pumped and through which the plunger extends, said pump body containing packing which frictionally engages the plunger, whereby it is caused to move with said plunger; a sleeve in which said extension slidably fits, said sleeve having a portion disposed in the path of the pump body to engage the confronting end thereof and thereby terminate the movement of said body in one direction; a centrally-perforated washer against which the upper end of the pump body is adapted to contact during the discharge

stroke of the plunger; and an elastic member disposed upon the upper face of said washer and having a central perforation in register with the perforation in the washer.

5 3. In a pump of the character described, the combination of a plunger having an extension which forms a guide therefor; means for reciprocating the plunger; a cylindrical pump body immersed in the liquid to be pumped and through which the plunger extends, said pump body having frictional engagement with the plunger, whereby said body is caused to move with said plunger; a sleeve in which said extension slidably fits,

10 15 said sleeve having its upper end confronting the lower end of the pump body to be engaged thereby so as to terminate the downward movement of the pump body with the plunger; a vertical rack on the side of said sleeve; and a pinion engaging said rack to raise or lower the sleeve toward or from the pump body and thereby vary the extent of movement of the latter with the plunger.

20 25 4. In a pump of the character described, the combination of a plunger having an extension which forms a guide therefor; means

for reciprocating the plunger; a sleeve wherein said extension slidably fits; a cylindrical pump body immersed in the liquid to be pumped and through which the plunger extends, said pump body having an enlarged portion containing compressed cork which frictionally engages the plunger so as to cause the latter to raise and lower the pump body with it; a thin perforated metal washer forming a stop against which the upper end of the pump body is adapted to strike; a hemispherical elastic washer resting at its flat under face on the metal washer and having a central perforation in register with the perforation in said metal washer; a valve seat for said elastic washer; and a spring acting against the lower end of the plunger to press the said upper end of the pump body against said metal washer.

45 In testimony whereof I have signed this specification in the presence of two subscribing witnesses.
